BUTTON SEWING ATTACHMENT FOR
SEWING MACHINES

Abraham Mosberg, New York, N. Y., assignor of
thirty per cent to David Fischbein, twenty per
cent to Max Kaufman, and twenty per cent
to Alex Fuchs, all of New York, N. Y.

Application May 5, 1950, Serial No. 160,367

4 Claims. (CL. 112—115)

1

The present invention relates to an improved button-sewing attachment for sewing machines.

The principal object of this invention is to provide a novel and improved attachment for a sewing machine, for sewing two-hole and four-hole buttons, with provision to adjust for distance between holes and with means to set the device for operation for the sewing of either kind of button of different sizes.

Another object hereof is to provide a button-sewing attachment of the character mentioned which is simple in construction, reasonably cheap to manufacture, easy and convenient to use and efficient in accomplishing the purposes for which it is designed.

Other objects and advantages will become apparent as this disclosure proceeds.

In the accompanying drawings forming part of this specification, similar characters of reference indicate corresponding parts in all the views.

Fig. 1 is a front view of a button-sewing attachment embodying the teachings of this invention. It includes a fixed frame adapted to be mounted on the presser foot bar of a sewing machine. On the bottom of the fixed frame is a movably mounted frame piece carrying an adjustable vise means for holding the button. Cams carried on the fixed frame, are given motion by a ratchet means operated by the reciprocating needle bar of the sewing machine; said cams being adapted to give the movable frame piece various required motions. These and other associated components will be fully described.

Fig. 2 is a top plan view of Fig. 1. Here, the button vise means is omitted in order to attain clarity of illustration.

Fig. 3 is a perspective view of the fixed frame included in this embodiment.

Fig. 4 shows the movable frame in perspective.

Fig. 5 shows in perspective, the parts used in the assembly of the fixed and movable frames.

Fig. 6 is a perspective view of a cam follower used in means for shifting the movable frame so that two holes in a button carried in the vise, are alternately presented to needle axis position.

Fig. 7 shows a cam included in this device, used in means to impart additional movements to the movable frame when four hole buttons are to be sewed.

Fig. 8 shows the cam follower and associated components which cooperate with the cam shown in Fig. 7. This view shows how the parts here illustrated appear in Fig. 1, when everything in front of them is removed.

2

Fig. 9 shows the button vise jaws in perspective.

Fig. 10 is a bottom view of a member included in the vise mechanism and particularly used to adjust the vise to required button size.

Fig. 11 is an end view of Fig. 10.

Fig. 12 is a top plan view of the movable frame, showing among other things, the button vise mechanism fully assembled and carried thereon.

10 In the preferred embodiment shown in the drawings, the numeral 15 designates what is here called the stationary or fixed frame, because when the device is to be used, the presser foot of the sewing machine 16 is removed, and this 15 frame 15 is fixedly mounted on the machine's presser foot bar 17 at the adapter block 18, as shown in Fig. 1. On this fixed frame is the rotatably mounted shaft 19 which carries the cam 20, the cam 21 and the ratchet wheel 22, all 20 fixed on said shaft. Carried loose on said shaft 19, is the arm 23, whose free end is bifurcated and adapted to receive the head of the needle's set screw 25 on the needle post 26 which holds the needle 27 extending downwardly. This arm 23 carries the pivoted pawl 28 whose tooth is in engagement with said ratchet wheel 22, and such engagement is maintained by the spring element 29. When the sewing machine is operated, it is evident that shaft 19 will be given intermittent rotary movement a part of a revolution at each 30 upward movement of the needle 27.

The movable frame piece denoted generally by the numeral 30, is here shown as a plate member having the notch 31 at one end which is at needle region of the machine, and a hole or slot 32 at 35 about central region. Also, it has the elongated slot 33 to serve as a track for element 87 of the vise jaw adjustment member 81; said slot 33 being in alignment with the notch 31 and hole 32 and between them, commencing from near 40 said notch. The movable frame or plate member 30 is positioned under the fixed frame 15, and mounted to the same by means of the screw 35 passed through the arcuately bent blade spring 36, then hole 32 and finally engaged in threaded hole 45 37 in the fixed frame 15, from which hole it extends upwardly to serve as a pivotal axis for the cam follower 38 which carries the roller 39 engaged in the cam 20.

Said cam follower member 38 is composed of 50 an L-shaped part at whose vertex is the roller 39, and at the extremity of one leg is the hole 40 for the axis pin 35. The other leg of said part has an integral bar 41 across it to make a 45 T-shape therewith; said part 41 being provided

55 with a slot 42 to receive the cam 20.

with a longitudinal slot 42. A similar slot denoted by the numeral 43 is provided in the movable plate 30. The cam follower 38 is associated to the movable plate 30 by means of a screw 44 positioned through both said slots. Such screw, carrying a fixed washer 45 and a wing nut 46, has freedom of movement along the slot 43 and is releasably fixed to the cam follower 38. Upon rotation of the cam 20, the movable plate 30 will be oscillated about point 35 as an axis, in the direction of arrows at line A—A. The scope of such oscillation should be the distance between the holes 47 and 48 of the button 49, and may be adjustably set by shifting the position of the screw 44, because the scope of movement of the movable plate 30, occasioned by rotation of the cam 20, is a function of the distance between the screws 35 and 44. It is evident that the operating assembly thus far described in detail, is for the sewing of two-hole buttons, with provision to adjust for distance between holes in the button.

It is to be noted that spring 36 is permitted longitudinal movement but no lateral movement in track means afforded by the downwardly struck parts 50 in the body of the movable plate 30, between which parts 50, said spring is positioned. In fact, it is said plate 30 which has the movement with respect to the length of said spring 36, and such is brought about by action of the cam 21, so that the button when of the four-hole variety, shall be given an oscillatory motion equal to the distance between the holes 48 and 51, as will be explained.

The numeral 53 denotes a bar which serves as the follower for the cam 21. One end of this bar is bifurcated as at 53' to set on the shaft 19. This bifurcated end is thin in comparison to the remainder of the body of this bar, so that there shall be a cam-bearing surface 53'' held in contact with the periphery of cam 21, by means of a tensed tension coil spring 54, one of whose ends is secured to said bar 53, and whose other end is fixed to the fixed frame member 15; such points of attachments being denoted by the numerals 55 and 56, respectively. The other end of bar 53 is pivotally linked at 57 to a plate 58 which is pivotally linked at 59 to the fixed frame member 15. Said plate 58, lying in vertical plane, is provided with the longitudinal slot 60, which intersects, or in one position of said plate, lies along the vertical slot 61 in the standard 62 integral with the movable plate 30. A shank or pin 63, having an intermediate shoulder 64, and a threaded end 65 for the wing nut 66, is adapted to be fixed at any desired point along slot 60, to the plate 58, so that said pin 63 extends through the slot 61. It is evident that upon rotation of shaft 19, the action of cam 21 and spring 54, will impart an oscillatory motion to the bar 53, and hence plate 30 will move up and back in the directions of the arrows of line B—B, a predetermined distance depending upon the distance between the axis 59 and the axis of the pin 63; said pin 63 being positioned at such point along slot 60, where the scope of movement of the plate 30 along B—B shall be the distance between holes 48 and 51 of the four-hole button 67.

To accomplish better joinder of the movable plate 30 with the fixed frame 15, and yet permitting the required movements of said plate member, I include the screw 68 carrying a suitably sized washer 69 across the bottom of said plate at slot 70; said screw extending upwardly and in threaded engagement with the fixed frame in the

threaded hole 71; the size of the slot 70 being large enough to permit all required movement of the plate 30.

So that the device be adaptable for the sewing of two-hole buttons or four-hole buttons, at the will of the operator, provision is made to hold the follower bar 53 in a position where it is out of the locus of movement of the cam 21. In the embodiment shown, said bar has the notch 72 to receive the dog or pawl 73, which is releasably fixed on the stationary frame member 15 by means of the screw 74 through a longitudinal slot 75 in said pawl. When the bar 53 is shifted by hand to permit setting of the pawl 73 in notch 72, so that said bar is made fixed to the frame 15 and out of the influence of the cam 21, the device is operative only by action of the cam 20 for the sewing of two-hole buttons. It is to be noted that in such position of the bar 53, its tines still straddle the shaft 19, so that mere disengagement from the said pawl 73, will make spring 54 to restore said bar 53 into operative contact with the cam 21, whereupon the device becomes operative by both the cams 20 and 21, for the sewing of four-hole buttons.

The cams 20 and 21 are so designed that cam 20 will oscillate the plate 30 a few times along the direction A—A while said bar 53 is at rest; such bar being at rest during two periods per revolution of the shaft 19; the arcual surfaces 21' and 21'' being of concentric circles of different radii with center at axis of the shaft 19.

The preferred button vise shown includes the pair of members 76 and 77, fashioned respectively with channelled jaws 76' and 77' at one of their ends, with their other ends pivotally mounted at 78 and 79 respectively, on the top surface of the movable plate member 30, and urged towards one another by the spring means 80. A plate member 81, lies across the jaw members 76 and 77, and is provided with the slots 82 and 83 which converge away from button position. The pins 84 and 85, fixed respectively in the jaw members, extend, one through each of said slots, and are of a diameter less than the width of said slots, to permit a little movement of the jaw members so that a button set between such jaws 76' and 77' will be spring gripped; the position of said plate member 81, determining the size of button adaptable for reception between the vise jaws. Said plate member carries a stop element 86, which together with the jaws, determines button position. Also, said plate member carries a small block element 87 which rides along the slot 83 in which it slidingly fits. Member 88, may be of a wire whose ends are secured at opposite points of the plate member 81, as at 89, and bent to form a handle element 90 and a slot 91 for the screw 92 in the plate member 30. Shifting handle element 90 to the right in Fig. 12, will cause the vise jaws to open further apart, and when shifted to the left, will bring the vise jaws closer together. Tightening the screw 92, will fix the position of the plate member 81.

Referring to Fig. 4, adjustment for button size may be aided by means of the graduations at 93; the positioning of the screw 44 may be aided by graduations 94 along the slot 43, and the positioning of the pin 63, may be aided by graduations 95 along the slot 61.

When the device is in use, the cloth feeder of the sewing machine is covered by a suitable plate, not shown, so that when the presser bar 17 is in its most downward position, components of the

device projecting below the under surface of the plate member 30, shall clear the machine table; reliance being had on the suitably roughened or serrated surface at 96 of the undersurface of said plate member, to carry the cloth on which the button is being sewn, along with the said plate member 30, in all its movements. Notch 97 in the blade spring 36, permits said spring in its movement to clear the screw 68 and washer 69. The relation of the design of cam 20 to needle movement, is well known in the art, and therefore needs no explanation, for same is well known in devices for sewing a two-hole button, or at most, to sew through two holes in a button. Some lateral adjustment is permissible in adapter block 18 for initial setting, to insure passage of the needle 27 through the holes 47 and 48. Once the device is set for a particular button, no further adjustment is necessary for a run of similar buttons. After the button is set in the vise and in contact with the stop element 96, all sewing is automatic when the machine is let run. Experience teaches the operator the proper time for each run, per button, in accordance with the desired stitch quantity.

This invention is capable of various forms and numerous applications without departing from the essential features herein disclosed. It is therefore intended and desired that the embodiment shown herein be deemed illustrative and not restrictive and that the patent shall cover all patentable novelty herein set forth; reference being had to the following claims rather than to the specific description herein to indicate the scope of this invention.

I claim:

1. A button sewing attachment for a sewing machine, comprising a frame member adapted to be fixedly mounted on the presser foot bar of a sewing machine, a shaft rotatably mounted on said frame member, a first cam and a second cam securely carried on said shaft, means for imparting uni-directional, intermittent rotary movements to said shaft, adapted to be operated by the needle bar of the machine; there being a plurality of such shaft movements during each complete revolution of said shaft, a plate member positioned under and connected to said frame member whereby said plate member is capable of being reciprocated on said frame member along a given line and across said line, a button holding means carried by the plate member, two separate cam follower means carried by the frame member, cooperating with said cams respectively to impart such respective motions to the plate member; the design of said cams being such that the first cam when rotated will impart a plurality of complete reciprocatory movements and the second cam when rotated will impart one complete reciprocatory movement to the plate member per revolution of said shaft; the first stroke of said one reciprocatory movement occurring at about the completion of a one half revolution of said

shaft and the return stroke occurring at about when the said shaft has completed one revolution and manually adjustable means on the frame member to releasably hold the second cam follower means stationary; the movements of the plate member being such when both said cams act to move it, one along said line and the second cam across said line, whereby a button having four holes determining a rectangle, carried by the button holding means, will move along with the plate member so that two of said holes will alternately be at needle position during one of the periods while the second cam is at rest and the other two of said holes will alternately be at needle position during the second period while the second cam is at its second rest per revolution of shaft.

2. A button sewing attachment as defined in claim 1, wherein the plate member is provided with a slot away from needle region and along the direction said plate moves when shifted on the frame by action of the second cam and wherein the connection between said plate and frame members includes an arched blade spring, and including track means on the underside of the plate member; said blade spring being slidably positioned in said track means for movement along same in said direction, a screw positioned through said slot in the plate member and engaging said spring and the frame member whereby said spring is tensed and the plate member is made swingable and slidable with respect to the frame member.

3. A button sewing attachment as defined in claim 1, wherein the second cam follower means is adapted to be held stationary though the second cam continues to move; said second cam follower means having a slot and a cam-contacting surface and comprising a bar; the shaft carrying the cams, extending through said slot and supporting said bar at all times.

4. A button sewing attachment as defined in claim 3, including a separate member having an upright slot; the bar being pivotally connected to such separate member at a point to one side near the bottom of said slot and said separate member being pivotally connected to the frame member at a point at the top and to the same side of said slot and wherein the movable plate member has an upright standard having a slot therealong; both said slots being near each other and a pin extending loosely through the slot in the said standard and manually adjustably securable at any desired point along the slot in said separate member.
